UNITED STATES PATENT OFFICE.

ARTHUR J. TOWNSEND, OF CANTON, OHIO, ASSIGNOR TO THE NATIONAL PRESSED STEEL COMPANY, OF MASSILLON, OHIO, A CORPORATION OF OHIO.

SHEET-SPLITTING MACHINE.

1,323,425.

Specification of Letters Patent.

Patented Dec. 2, 1919.

Application filed May 28, 1917. Serial No. 171,445.

To all whom it may concern:

Be it known that I, ARTHUR J. TOWNSEND, a citizen of the United States, residing at Canton, in the county of Stark and State of Ohio, have invented a new and useful Sheet-Splitting Machine, of which the following is a specification.

The present invention relates to machines for splitting sheets or light plates of metal into any desired number of strips of uniform width throughout their entire lengths and provides means for also trimming the outer edges of the sheets from which the strips are cut.

15 The object of the present invention is to provide a machine which in one operation will split a sheet or light plate into a plurality of strips of any desired width.

A further object is to provide a machine 20 for the purpose described in which the sheet or light plate to be split may be fed continuously therethrough thus greatly reducing the time heretofore required for the manufacture of a given quantity of the 25 product.

A further object is to provide means whereby the parts of the machine may be adjusted in order to cut strips of various widths.

30 With these objects in view the invention consists in the novel construction and arrangement of parts, hereinafter described, illustrated in the accompanying drawings, and particularly pointed out in the appended 35 claims, it being understood that various changes in the form, proportions, size and minor details of construction may be made within the scope of the appended claims, without departing from the spirit or sacrificing any of the advantages of the invention.

In the accompanying drawings:

Figure 1 is a top plan view of a machine constructed in accordance with my invention.

45 Fig. 2 is a longitudinal section therethrough.

Fig. 3 is a sectional view on an enlarged scale of a pair of the co-acting cutter disks.

50 Similar numerals of reference indicate corresponding parts throughout the several figures of the drawings.

Referring more especially to the construction illustrated in the accompanying draw-

ings, the numerals 1—1 indicate the side 55 frames which may be of any desired size and form and which are mounted upon the base 2 which is preferably rectangular as best shown in Fig. 1. Feed rolls 3 are journaled between the frames 1—1 at the forward extremity of the machine and are arranged to rotate in opposite directions to feed the sheets or plates of metal, desired to be slit, through the machine, a power pulley 4 being provided upon the shaft 5 of one 60 of said feed rolls for the purpose of imparting motion to both of the feed rolls and to the splitting disks as will be hereinafter described.

Spaced pairs of shafts 6—6, 7—7, 8—8 70 and 9—9 are journaled between the frames 1—1 beyond the feed rolls 3 and each of the shafts 6, 7 and 8 is provided with a pair of spaced adjustably mounted collars 10 while the shafts 9 are each provided with only 75 one of said collars. These collars are so arranged that each adjacent upper and lower collar are mounted in juxtaposition to each other. It will, of course, be understood that any other arrangement of the positions of 80 the pairs of collars may be provided and more or less shafts than are shown in the drawings may also be used without altering the principle of the invention.

Each of the collars 10 is provided upon 85 one face with a circumferential recess 11, in which is located a cutting disk 12 connected to the collar by means of screws 13 or their equivalents. Each collar 10 is provided with an enlarged central aperture 14 preferably 90 having annular shoulders 15 around each face of the collar at the extremities of said aperture and each collar is adjustably mounted upon the screw threaded portion 16 upon the shaft by means of a pair of nuts 95 17 which have annular flanges 18 arranged to contact with the shoulders 15 of the collars, bosses 19 being provided on the outer faces of said nuts for the purpose of applying a suitable tool to turn them.

An inspection of Fig. 1 of the drawings 100 will readily show that the cutting disks upon each succeeding shaft are located closer to the longitudinal center of the machine than the disks upon the next preceding shaft. By 105 this construction the disks upon the shafts 6 will trim the outer edges of the sheet or plate as it passes between said disks, the

disks upon the shafts 7 will cut a strip of the desired width from each side of the sheet or plate, the disks upon the shafts 8 will cut two further strips of the desired width and 5 the disks upon the shafts 9 will cut the remaining portion of the sheet or plate into two further strips.

Located beyond the shafts 9 is a pair of delivery rolls 20 arranged to receive the 10 strips which have been cut and deliver the same from the machine. In order that all of the rolls and cutter disk shafts may be operated in the proper direction simultaneously to carry a sheet or plate through 15 the machine and properly split the same, gears 21 are provided upon each of the cutter disks and roll carrying shafts, the upper and lower gears meshing with each other in the usual manner and the pinions 22 meshing with said gears in order to drive all of 20 the rolls and cutter disks in the proper direction.

For the purpose of guiding the sheets or plates through the machine, guide bars 23 25 are located transversely across the machine and in a direct horizontal plane with the under faces of the sheets or plates. In order to prevent the strips from buckling or bending as they pass through the cutters a pair 30 of pinch rollers 24 is provided between each set of shafts and in a horizontal plane to receive the strips therebetween for the purpose of keeping the strips in alinement and to also insure their properly entering the next 35 succeeding set of cutter disks.

All such machines heretofore constructed have proven impracticable and imperfect, the defect having been that several of the cutting disks were arranged on one shaft or 40 so that their axis of rotation came in the same line, and as a consequence of this arrangement, if the sheet or plate failed to present itself in the proper position to the cutters it was wedged or bound between 45 them. The above difficulty is obviated in the present machine by arranging the cutting disks in two converging lines so that the disks first contact with the sheet or plate near its outer edges and then successively 50 cut nearer and nearer to the center cutting

one strip after another from each side of the sheet or plate.

A further advantage of the present machine which has not been found possible in any of the machines of this character in use 55 at the present time is that owing to the construction of the machine and the possible adjustments of the cutting disks upon the shafts, the machine may be quickly and readily adjusted to permit very narrow 60 strips to be cut thereby. With this construction it is possible to cut strips of metal of a uniform width of less than a quarter of an inch, thus making it possible to cut strips of the narrowest width which may be required for practical purposes.

Although the drawings and above specification disclose the best mode in which I have contemplated embodying my invention I desire to be not limited to the details 70 of such disclosure, for, in the further practical application of my invention, many changes in form and construction may be made, as circumstances require or experience suggests, without departing from the spirit 75 of the invention, within the scope of the appended claims.

I claim:

1. In a machine of the character described, a shaft provided with a screw 80 threaded portion, a pair of circular nuts mounted upon the screw threaded portion, an annular flange around the outer side of each nut, and a cutting disk provided with a central aperture arranged to receive said 85 nuts and provided with an annular shoulder at each end of the aperture to engage the flanges upon the nuts.

2. In a machine of the character described, a frame, a series of shafts journaled 90 in said frame and cutting disks mounted upon said shafts and arranged in two converging lines, each of said cutting disks having a central aperture and an annular shoulder formed upon each face and a pair of 95 nuts engaging the shaft and arranged to engage said annular shoulder.

In testimony that I claim the above I have hereunto subscribed my name.

ARTHUR J. TOWNSEND.
